UNITED STATES PATENT OFFICE

1,990,284

SEWING MACHINE HEMMER

Charles Bennett Hinds, Scranton, Pa.

Application April 26, 1933, Serial No. 668,113
Renewed November 28, 1934

1 Claim. (Cl. 112—147)

This invention relates to a hemmer attachment for sewing machines, and the object of the invention is to provide such an attachment which may be readily mounted on any conventional type of sewing machine, and in a manner to be readily swung upwardly out of the way when not in use, without being detached from the machine.

The invention, together with this and numerous objects and advantages will be best understood from a study of the following description, taken in connection with the accompanying drawings, wherein is illustrated a preferred embodiment of the invention.

It is understood that the invention is not to be limited to the precise details of construction, combination and arrangement of elements as illustrated and described, other than might be necessary to meet the requirements of prior art, and the scope of the appended claim.

Other objects and advantages will be best understood from a study of the following description, taken in connection with the accompanying drawings, wherein:

Figure 1 is a side elevational view showing the hemmer mounted in positive position on the head of a sewing machine.

Figure 2 is a front elevational view of the hemmer.

Figure 3 is a perspective view of a bracket plate forming a part of the invention.

Figure 4 is a side elevational view of the hemmer with the same shown swung up in an out of the way position.

Figure 5 is a fragmentary sectional view through the pivot connection between the attaching bracket and arm.

Figure 6 is horizontal sectional view through the attachment, and

Figures 7 and 8 are sectional views taken substantially on the lines 7—7 and 8—8 respectively, of Figure 6.

Referring to the drawings by reference numerals, it will be seen that 10 indicates generally the head of a conventional type of sewing machine, 45 while the hemmer attachment is designated generally by the reference character 11.

The attachment 11 comprises an attaching or bracket plate 12, that is adapted to be mounted on the lower end of the head transversely of the head, and to be secured thereto through the medium of screws or other fastening elements 13. An angular tapered arm 14 has the largest end thereof pivoted to the bracket plate 12, through the medium of a pivot bolt 15, that extends through 55 an aperture in the largest end of the arm 14, and

is threadedly engaged with a threaded aperture 16 provided in the forward end of the plate 12. A substantially conical coiled spring 17 is disposed about the bolt 15 and the largest end of the spring 17 bears against the arm 14, and at the smallest end, said spring seats against the head of the bolt 15, in a manner clearly shown in Figure 5, for urging the pivoted end of the arm 14 into frictional engagement with the plate 12, for holding the arm 14 at the desired position, as for example, the position as shown in Figure 1 when the device is in use, and the position shown in Figure 4 when the device is swung upwardly to an out of the way position when not in use.

On the free end of the arms 14, there is secured 15 in any suitable manner, as by being soldered thereto, an edge turner or holder, which, in the present instance, comprises upper and lower substantially parallel wings 18, 19, which at one edge merge into concentric downwardly directed 20 curved walls, 20, 21, which merge into the side walls of a channel 22, as will be clear from a study of Figures 7 and 8. The channel 22 is disposed at an incline to the plates or wings 18, 19, with the top wall of the channel 22 being remote 25 from the lower plate or wing 19 at one end of the device, and at a relatively opposite end being contiguous with said wing 19, as also will be clear from a comparison of Figures 7 and 8. Further, as shown in Figure 1, the holder is disposed 30 at an incline to the horizontal, sloping rearwardly or in the direction of the stitch forming mechanism of the machine, as will be clear from a study of Figure 1.

To facilitate insertion of the cloth into the 35 space between the wings 18, 19, the walls 20, 21, of the channel 22, and the free edges of the wings 18, 19, are reversely bent as at 23, 24, respectively.

On the front face thereof, the plate 12 adjacent its forward end is provided with a stop block 25, with which is engageable one edge of the arm 14 when the latter is in the perpendicular position shown in Figure 1, that is, in the position for use in holding the cloth as it is guided to the 40 stitch forming mechanism of the sewing machine.

In operation, the edge of the cloth to be 45 hemmed is inserted into the holder passing between the wings 18, 19, downwardly between the 50 walls 20, 21, and into the channel 22, as shown in Figure 6. In this manner, as the cloth passes through the holder, the edge of the cloth will be turned under for subsequent stitching in the 55 forming of the hem, in a manner well known and

thought to be apparent. By passing the cloth under the device with a portion of the cloth engaging the free edge of the wing 19, a large fold will be formed in the cloth and the hem will be 5 sewn to the cloth directly under the channel 22 so that a casing or large hem will be formed in the cloth.

Owing to the manner in which the hemmer 10 is supported on the head 10 by the bracket plate 12 and pivoted arm 14, it will be obvious that said hemmer may be turned up out of the way to the position shown in Figure 4, and will be frictionally retained in this position through the medium of the pressure of the spring 17 against the 15 arm. The tension of the spring 17 may be adjusted as found desirable by adjusting the pivot bolt 15, as is apparent.

Even though I have herein shown and described the preferred embodiment of the invention, 20 it is to be understood that the same is susceptible of further changes, modifications and improvements coming within the scope of the appended claim.

Having thus described my invention, what I 25 wish to claim as new is:

A sewing machine hemmer adapted for attachment to the head of a sewing machine and

comprising an arm, means for attaching one end of the arm to a part of the head, a folding device on the free end of said arm, said folding device comprising upper and lower substantially parallel wings adapted to receive therebetween the edge portion of the cloth to be hemmed, depending curved walls depending from said wings at one edge of the latter, and a channel disposed beneath the lowermost one of said plates and having side walls merging with the depending walls of said wings, the curved walls serving to guide the edge of the cloth into the channel during passage of the cloth through the holder in the direction of the stitch forming mechanism of the machine the lower wing being wider than 15 the upper wing and having a straight side edge and the channel part being spaced from the lower wall at the front of the device, with the upper wall of the channel part contacting the lower face of the lower wing at the rear of the device, the upper wall of the channel part and that portion of the lower wing immediately above said wall converging from the front of the device to the rear thereof, with the device sloping downwardly and rearwardly from its front end. 20 25

CHARLES BENNETT HINDS.
